MACHINE FOR CUTTING RHOMBIC SECTIONS FROM SHEET PILES

William R. Fisher, Arlington, N. J., assignor to Reynolds Metals Co., Richmond, Va., a corporation of Delaware

Application January 13, 1943, Serial No. 472,182

8 Claims. (CL 164—59)

This invention relates to new and useful improvements in sheet cutting machines of the guillotine class wherein substantially thick piles of rectangular printed sheets are cut into a plurality of rectangular piles of labels and the like.

In case the geometrical contours of printed labels are not rectangular, it is the general practice to die-cut such formations. Die-cutting obviously necessitates allowable marginal wastage of the label materials for each label. Comparatively few sheets can be die-cut each operation due to the vertical cutting action of the die. To prevent resulting distortion of sheets and the tendency to draw out of cutting register, each of these sheet piles must be bound together. Again the top sheet of each pile is treated with a lubricant to lubricate the cutting edge of the die. This sheet of component labels is also wasted.

By means of the invention rhombic labels may be printed on sheets of any desired size and in successive rows so that at the end of each row only a small triangular unprinted and waste section is proved. These sheets are piled and the rows are separated by cutting into row-piles of printed strips having the small triangular waste sections at their ends. The row-piles are then turned angularly to the said initial lines of cut, in such manner that the triangular waste areas assume ladder formation so that a single guillotine cut through the row-piles at each end will remove all of the triangular waste sections at that end. The row-piles, after removal of the waste at one end, may be moved forwardly by steps each followed by a cutting action separating individual piles of completely cut labels. Such action employs three primary elements mounted on the bed of the cutting machine, namely; an auxiliary back wall having sliding motion on a back gauge which moves toward the knife, an adjustable side gauge which controls the endwise movements of the slideable auxiliary back wall, and yielding sections carried by both the side gauge and the auxiliary back wall.

The invention will be described with reference to the accompanying drawings, in which—

Figure 1 is a front elevation showing a cutting machine with my improvements carried thereby.

Figure 2 is a rear view of said embodiment, and in elevation;

Figure 3 is an enlarged fragmentary view showing in plan the forward portion of the machine bed with a stack consisting of piled label strips in position for an initial cutting action at the forward ends thereof.

Figure 4 is a view similar to Figure 3 showing the position of the parts after successive cutting actions have been performed.

Figure 5 is a fragmentary view in elevation taken at the line 5—5, Figure 3 with the stack clamping bar raised.

Figure 6 is a view similar to Figure 5 with the stack clamp down and in clamping position.

Figure 7 is a vertical section taken on the line 7—7, Figure 3 and through the bed and side gauge and partially through the auxiliary back wall, illustrating a construction of the latter in which it is spring-yielding and hence is adapted to move under the pile clamp in the final cutting movement of the knife, that is to say, prior to said final cutting movement.

Figure 8 is a vertical section on the line 8—8, Figure 7.

Fig. 9 is a diagrammatic showing illustrating the upper portion of one of the finished sheets prior to its severance into rows.

Referring to the drawings, it will be understood that the improvements may apply to any suitable design of cutting machine of the guillotine type, and that the knife-operating and pile-advancing mechanisms of the machine indicated in the drawings are only generally shown and are not illustrated in detail, because they form no part of the present invention. The machine indicated comprises a supporting base 1, a bed 2, upwardly-rising knife guides 3 and a guillotine knife 4. Power is derived from a motor 5, a pulley 6 on the motor shaft receiving a belt 7 which rotates the main drive shaft 8 through its pulley 9, the shaft 8 being suitably connected with a shaft 10 having operative connections with an arm 11 connected to one end of the knife and also having operative connections with an arm 12 connected to the opposite end of the knife; these arms having such motion that in the downward and cutting movement of the knife the latter has a shearing motion to the left from its position when raised as in Figure 1.

Referring to Figures 2 to 4 inclusive, it will be seen that the bed 2 carries a usual type of forwardly and backwardly moving back gauge 13 which in practice is power-advanced and retracted by motion imparted to push-and-pull rod 14.

The auxiliary back wall

Slidably mounted on the forward face of the back gauge 13 is an auxiliary back wall having two relatively movable sections, the front section being shown at 15 and the rear section at 15x. The rear section consists of a plate having a for-

wardly-projecting flange at its base, the plate being formed with a slot at *s*, which slot extends longitudinally. Carried by the back gauge are two headed studs *16*, the shanks of which pass through slot *s* of the auxiliary back wall, the shanks or stems being threaded to receive holding nuts *16x*. The horizontal flange of member *15x* carries a plurality of upwardly projecting posts to serve as holding-guides for coil springs *17*, which springs normally hold plate *15* upwardly in the position shown in Figure 7.

It will be seen from the above that the auxiliary back wall is mounted to slide longitudinally of the back gauge and that it moves forwardly bodily with the back gauge. At one end the auxiliary back wall has pivoted thereto at *18* an arm *19* which is slotted to receive a stud shaft *20* carrying a roller *21*, the shaft being held in adjusted position by a nut *22* on its threaded end. Also, a roller *23* may be mounted on the pivot stud at *18*.

The adjustable side gauge

The rollers *21*, *23* contact with the opposite guide faces of an adjustable side gauge *24* which is fixed in its adjusted position on the bed *2*. Within a longitudinal slot in the side gauge lies a pivot stud *25* carried by the bed, and pivoted to the side gauge at *26x* is a slotted arm *26*, the shank of a wing nut *27* which passes through the slot and is threaded in the bed *2*, holding the side gauge in adjusted position.

The compressible end of the side gauge

The forward end of the side gauge lies under the power clamp *28*. This is the clamp which moves downwardly to firmly hold the rows of piled labels firmly in position immediately prior to the descent of the knife. The said forward end of the side gauge is compressible. To that end it is formed in two sections, a lower section *29* carrying spring-receiving studs and these studs receiving spiral springs *30* which normally hold the upper section *29x* upwardly in the position of Figure 5. When the power clamp *28* moves downward and to the position of Figure 6, the side gauge compressible and member *29x* moves downwardly, and when the pile clamp raises member *29x* moves upwardly with the released pile to maintain full guiding effect.

The nature of the printed sheets which are cut in pile formation

Figure 9 diagrammatically illustrates the upper portion of one of the finished sheets prior to its severance into rows, with each row constituting a plurality of unsevered labels of rhombic design. The individual labels are indicated at *31* and the triangular end waste sections at *32*. The first step is to cut a pile of the label sheets into rows, the lines of cut being indicated at *33*. These rows are then laid upon the bed and, with reference to Figure 3, are swung over into the angular position shown in that figure, whereupon the lines *34* between the labels of each row will be brought end-to-end and in straight-line parallelism throughout the rows, the lines of parallelism being synchronous with the knife.

The back gauge is then moved forwardly a distance sufficient to bring the forward waste end portion of the assembled rows into cutting registry with the knife, whereupon the pile clamp *28* is brought down, followed by corresponding movement of the knife, and the small triangular waste ends are removed from all of the pile rows by a single motion of the knife.

The next action is to move the back gauge forwardly a distance corresponding with the length of the labels or the distance between any two of the dotted lines *34*, Figure 3. The pile clamp again moves downward, followed by the knife, and the first set of completely cut rhombic labels is produced, that set constituting as many stacks as there are rows. In the descent of the pile clamp the forward end of the side gauge is compressed, as earlier explained, and the rise of the pile clamp will restore the said compressible end of the side gauge to initial position. In the step-by-step forward movement of the back gauge, the auxiliary back wall is given successive endwise movement through the engagement of rollers *21* and *23* with the side gauge.

It will be noted that only one side gauge is necessary, because the side gauge illustrated is so positioned that the downward and endwise motion of the knife is directed toward it, and the mutual contact of the pile rows is sufficient to hold the rows in position, aided by the action of the side gauge in restraining the tendency of the rows to shift. In all cases, however, the pile clamp is the primary row-holding and restraining element during action of the knife.

When all of the labels have been cut there will still remain triangular projections at one end of the final set of labels, and in the severance of such projections, they, alone, must be held by the pile clamp. For that reason, my improvements enable the auxiliary back wall to move under the pile clamp and afford an adequate back stop. As earlier explained, such action is made possible by forming the auxiliary back wall into a rigid holding section and an outermost yielding section, the latter moving downward when the pressure of the clamp is applied.

By means of the invention, expensive die-cutting is eliminated and production is greatly increased, the means employed being relatively simple in form and of relatively low cost.

Having described my invention, what I claim, and desire to secure by Letters Patent, is as follows:

1. In sheet cutting machines of the guillotine class, and in combination with a cutting bed, a pile clamp, a reciprocatory cutting knife and means for operating the same, of a back gauge, an auxiliary back wall carried by and movable longitudinally of the back gauge, a side gauge, and means intermediate the auxiliary back wall and the side gauge for effecting endwise movement of the auxiliary back wall upon bodily movement of the back gauge toward the knife.

2. In sheet cutting machines of the guillotine class, and in combination with a cutting bed, a pile clamp, a reciprocatory cutting knife and means for operating the same, of a back gauge, an auxiliary back wall slidable relatively to the back gauge, and a side gauge adjustable upon the bed to various angular positions relatively to the knife.

3. In sheet cutting machines of the guillotine class, and in combination with a cutting bed, a pile clamp, a reciprocatory cutting knife and means for operating the same, of a back gauge, an auxiliary back wall slidable relatively to the back gauge, a side gauge adjustable upon the bed to various angular positions relatively to the knife, and contact means carried by the auxiliary back wall and engaging the side gauge whereby during movements of the auxiliary back

wall toward the knife said wall is shifted endwise.

4. In sheet cutting means of the guillotine class and in combination with a cutting bed, a pile clamp, a reciprocatory cutting knife and means for operating the same, of a member movable on the bed toward the knife and adapted to engage pile rows of printed sheets to be cut, means for moving said member toward the knife, a side gauge adjustable upon the bed to various angular positions relatively to the knife, and means acted upon by the side gauge for shifting the pile-engaging movable member to shift the latter endwise upon movements thereof toward the knife.

5. In sheet cutting means of the guillotine class, and in combination with a cutting bed, a pile clamp, a reciprocatory cutting knife and means for operating the same, of a member movable on the bed toward the knife and adapted to engage pile rows of printed sheets to be cut, means for moving said member toward the knife, a side gauge adjustable upon the bed to various angular positions relatively to the knife, and rollers carried by said pile-engaging member and engaging opposite faces of the side gauge.

6. In sheet cutting machines of the guillotine class, and in combination with a cutting bed, a pile clamp, a reciprocatory cutting knife and means for operating the same, of a back gauge, an auxiliary back wall slidable upon the back

15 gauge and consisting of upper and lower spring-separated sections, whereby the auxiliary back wall is compressible, a side gauge adapted to be held upon the bed in various angular positions 5 relatively to the knife, and means for shifting the auxiliary back wall endwise in movements of the back gauge toward the knife.

7. A sheet cutting machine of the guillotine class constructed in accordance with claim 5, 10 in which the side gauge at its end section nearest the knife is formed with a compressible section member, and spring means engaging said compressible member.

8. In sheet cutting machines of the guillotine class, and in combination with a cutting bed, a pile clamp, a reciprocatory cutting knife and means for operating the same, of a back gauge, 15 an auxiliary back wall having a longitudinal slot, means passing through the slot and carried by the back gauge for holding the back wall on the back gauge for sliding movement, a side gauge adjustable upon the bed to various angular positions relatively to the knife, rollers carried by the auxiliary back wall and engaging 20 the side gauge, and power means for moving the back gauge toward the knife whereby the auxiliary back wall is acted upon by the side gauge and is given endwise movement.
